UNITED STATES PATENT OFFICE.

WILLIAM HENRY HARRISON, OF NEW YORK, N. Y.

DEVICE FOR USE IN PLAYING POOL OR BILLIARDS.

Specification of Letters Patent.

Patented Apr. 8, 1919.

1,299,720.

Application filed April 19, 1918. Serial No. 229,640.

To all whom it may concern:

Be it known that I, WILLIAM HENRY HARRISON, a citizen of the United States, and a resident of city and county of New York, 5 borough of Manhattan, State of New York, have invented certain new and useful Improvements in Devices for Use in Playing Pool or Billiards, of which the following is a specification.

10 My invention relates to an auxiliary device for use in the playing of pool or billiards, and has for its principal object the provision of a device whereby the making of shots or strokes in which the cue is held 15 substantially vertically, such as massé shots, is facilitated. In making such shots it is customary to hold and guide the lower end portion of the cue by hand, this generally requiring the player to assume an awkward 20 position, which is objectionable not only because it is uncomfortable but also because it is apt to interfere with the accuracy of the shot. In accordance with my invention I 25 obviate this difficulty by providing a device by which the lower portion of the cue is held in position and guided so as to permit the cue to move in a substantially vertical direction into engagement with the ball, the player being left free to assume a more 30 comfortable position than heretofore in the making of such shots. The facility of making such shots is thereby greatly increased.

Another object of my invention is to provide an improved device of the character 35 described which can be readily collapsed into compact form for transportation and readily set up from collapsed form into condition for use.

40 Further objects and advantages of the invention will appear more fully from the following description taken in connection with the accompanying drawings forming a part of this specification and illustrating two approved embodiments of the invention.

45 In the drawing,

Figure 1 is a perspective view illustrating the use of the preferred embodiment of my invention on a billiard table, only a portion of the table being shown;

50 Fig. 2 is a side elevation, partly in section, of the said embodiment of my invention, some of the parts being shown in dotted lines in collapsed or folded positions;

Fig. 3 is a top plan view of the same;

55 Fig. 4 is a side elevation illustrating a modification of the invention applied to an

ordinary bridge rest, only a portion of the handle of the bridge rest being shown; and

Fig. 5 is a rear view of the same.

Referring to the drawings, and first more 60 particularly to Figs. 1, 2 and 3, the numeral 1 designates a flat horizontal base adapted to rest upon the billiard table A as shown in Fig. 1. Extending upwardly from the base 1 from a point in proximity to the periphery 65 thereof is a vertical standard or upright member 2, which carries at its upper end a flat horizontal member 3 formed with guides 4 either of which is adapted to hold the lower portion of the cue in position to permit the cue to move in a substantially vertical direction into engagement with the billiard ball, as will appear from an inspection of Fig. 1, in which the cue is represented by the character B and the balls are 75 represented by the character C. The guides 4 may be made of any suitable shape for effectively retaining the lower end of the cue in proper position, being preferably formed to extend entirely around the lower end portion of the cue. By making the openings 80 through the guides diamond shaped, as shown, the cue will be effectively held against lateral movement by adjacent sides of the opening when held to rest against 85 said sides. The walls of the said openings are best curved convexly in a vertical direction to facilitate the movement of the cue through the guides when the cue is inclined to different angles and to minimize wear. 90

The member 3 should be of sufficient height above the lower surface of the base 1 and the guides 4, a sufficient distance forwardly of the member 2 and the base 1 to 95 permit the guides 4 to be arranged over the ball in suitable position so that the guided cue can be moved into engagement with the ball for making shots of the character in question. The guides 4 should be of sufficient size to permit free movement of the 100 cue vertically or at a slight angle to the vertical. The normal height of the member 3 above the lower surface of the base may advantageously be made about twice the diameter of the ordinary billiard ball, and 105 the length of the inner sides of the guide rings 4 may advantageously be made about three-sixteenths of an inch greater than the diameter of the portion of the cue with which the rings co-act; but it is to be understood that other dimensions may be used, 110 those specified being merely for purpose of

illustration. To increase the serviceability of the invention by adapting it for use under a greater number of conditions the standard 2 is desirably made extensible so that the guides 4 may be adjustably and operatively positioned at different heights above the base 1. As shown the said standard is formed of two telescopically connected parts rectangular in cross section to avoid relative rotation thereof, the outer part 20 being connected to the base 1 and the inner part 21 to the member 3. A set screw 22 adjacent the upper end of the part 20 serves to hold the parts 20 and 21 in adjusted relation to each other. The construction, as shown permits the elevation of member 3 to approximately twice its normal or lowest height above the base 1. The base 1 is desirably made in substantially triangular form with the member 2 arranged substantially at the apex of the triangle, this arrangement permitting the device to be in some cases more readily positioned in operative relation to the ball to be struck, the apex of the triangle being adapted to extend in the space between the two closely adjacent balls, as will be evident.

With a view to making the device capable of being collapsed for a greater convenience in transportation, I connect the members 1 and 2 for relative pivotal movement about a horizontal axis 5 and I connect members 2 and 3 for relative pivotal movement about a horizontal axis 6, these axes being so arranged that the member 3 may be folded down flat upon one side of the upright 2 while the base member 1 may be folded flat on the opposite side of the upright 2, as shown in dotted lines in Fig. 2. The member 2 is desirably formed so that its lower end engages the top of the member 1 to prevent further angular movement of the said members away from each other when they have assumed operative positions with respect to each other. Various means may be employed for holding the members 1 and 2 in proper operative relationship, but I prefer to employ a brace such as that shown at 7, which is pivoted, as shown at 8, between projections 9, extending rearwardly from the upright 2 at a position suitable to permit the members 1 and 2 to be folded into engagement with each other without obstruction from the said projections. This brace is detachably secured at its lower end to the base 1 desirably adjacent the rear edge portion thereof as by thumb-screw 8', which passes through the lower end portion of the brace and is threaded into a bushing 9' secured in the said base. The pivot 8 is arranged at a suitable distance to the rear of the upright 2 to permit the brace 7 when disconnected from the base 1 and when the base 1 is in the dotted line position shown in Fig. 2, to move into engagement with the

bottom or outer side of the base, as shown in dotted lines in said figure. The member 3 may be held in adjusted position in any suitable manner as by the thumb-screw 10 constituting the pivot between the members 2 and 3. From the foregoing, it will be readily seen that by loosening the screw 10 and removing thumb-screw 8', the rest may be collapsed as shown in Fig. 2 with the brace 7, base 1, upright 2, and guide member 3 superposed. When thus collapsed the device is very compact and may be readily carried about in the pocket of the user. To set the same up it is merely necessary to move the parts 1 and 2 to proper operative angular relation, securing the brace 7 to the base 1 by means of the thumb-screw 8, lifting the member 3 to operative position and securing the same in such position by the thumb-screw 10. When desired the guide member 3 may be elevated above the base to an extent greater than that shown by first loosening set screw 22, which is again fastened when the desired adjustment has been made. When the said parts are thus adjusted they form a rigid device providing a firm guide for the cue. The member 7 serves not only to hold the parts 1 and 2 in proper angular relationship but also provides a convenient handle for the device.

The various parts referred to may be made of any suitable material, the base 1, upright 2 and guide member 3 being desirably made of brass although they may be made of wood, celluloid or other material. To increase the frictional hold of the device upon the table and at the same time to insure against the marring of the table, I provide the lower surface of the base 1 with a covering 11 of suitable material, such as velvet or felt. The brace and handle member 7, as shown, is formed with a body portion 12 secured upon a base member 14, the latter member being desirably made of strong durable material, such as a strip of sheet metal, which provides suitable extensions beyond the ends of the body member 12 whereby the member 7 is hinged to pivot 8 and adapted to be secured to the base 1. The body portion 12 may be of any suitable material, such as wood, and may be secured to the base member 14 in any suitable manner, as by screws 15.

In using the device it is positioned upon the table in a proper relation to the ball to be struck, as shown in Fig. 1, in which position it may be conveniently held, if desired, by grasping the handle 7 with one hand as shown, the body of the player being left free so that he can readily and accurately make the desired stroke with the other hand.

In Figs. 4 and 5 I have shown a modification in which the upright 2' is adapted to be detachably secured to an ordinary bridge

rest 15', as by an ordinary spring clamp, the member 2' having pivoted thereto, as at 16, 16' a jaw 17 which is arranged to co-act with the said member 2' to grip opposite faces of the bridge rest. The jaw 17 is, as shown, held in operative position by spaced compression springs 18, interposed between the member 2' and portions of the jaw 17 projecting above the pivots 16, 16'. The lower edges of the members 2' and 17 are preferably beveled downwardly and outwardly, as shown at 19 and 20, so as to facilitate the movement of the attachment into operative position downwardly over the upper edge of the bridge rest. The form of the invention shown in these figures has the member 3' which is provided with the guides for the cue formed integrally with the member 2', the member 3' corresponding in arrangement and shape with the corresponding part 3 in Figs. 1, 2 and 3. The use of this device is similar to that shown in Figs. 1, 2 and 3 and will be evident from the foregoing description.

25 While I have shown only two embodiments of my invention, the latter is susceptible of a variety of modifications, and it is to be understood that I do not limit myself to the details herein shown and described except to the extent explicitly expressed in any given claim.

Having described my invention, what I claim as new and desire to secure by Letters Patent is:

35 1. A device for use in playing pool and billiards, said device being adapted to rest on a pool or billiard table, and having a guide whereby the cue may be moved in a substantially vertical direction above and into engagement with a pool or billiard ball.

40 2. A device for use in playing pool and billiards, said device being adapted to rest on a pool or billiard table, and having a guide arranged to extend substantially more than half way around the cue whereby the cue may be moved in a substantially vertical direction above and into engagement with a pool or billiard ball.

3. A device for use in playing pool and billiards, said device being adapted to rest on a pool or billiard table, and having a guide arranged to extend entirely around the cue and to guide the cue for movement in a substantially vertical direction above and into engagement with a pool or billiard ball.

4. A device for use in playing pool or billiards, said device being adapted to rest on a pool or billiard table, and having a plurality of means, each arranged to guide the cue for movement in a substantially vertical direction above and into engagement with a pool or billiard ball.

5. A device for use in playing pool and billiards, comprising an upwardly extending

member, means projecting forwardly thereof for guiding the cue to permit movement thereof in a substantially vertical direction and a horizontal base supporting said upwardly extending member.

70

6. A device for use in playing pool and billiards, comprising an upwardly extending member, means projecting forwardly thereof for guiding the cue to permit movement thereof in a substantially vertical direction 75 and a horizontal base supporting said upwardly extending member, said base being adapted to rest on a billiard table and being provided at the bottom thereof with suitable means to obtain a frictional hold on the table without damaging the same.

7. A device for use in playing pool and billiards, comprising an upwardly extending member, means projecting forwardly thereof for guiding the cue to permit movement 85 thereof in a substantially vertical direction, a horizontal base supporting said upwardly extending member, and a handle connecting said upwardly extending member and base.

8. A collapsible device for use in playing pool and billiards, comprising a normally upwardly extending member provided with outwardly extending means for guiding the cue for movement in a substantially vertical direction above and into engagement with a 90 pool or billiard ball, a member supporting said first named member, and a brace for holding said members in operative relation at an angle to each other, said members and said brace being connected for relative movement permitting the collapsing of the device.

9. A device for use in playing pool and billiards, comprising an upwardly extending member, means projecting forwardly thereof for guiding the cue to permit movement thereof in a substantially vertical direction and a horizontal base supporting said upwardly extending member, said parts being connected for relative movement to permit collapsing the device so that said 105 parts extend substantially in the same direction.

10. A device for use in playing pool and billiards, comprising an upwardly extending member, means projecting forwardly 115 thereof for guiding the cue to permit movement thereof in a substantially vertical direction, a horizontal base supporting said upwardly extending member, and a handle connecting said upwardly extending member and base, said parts being connected for relative movement to permit the collapsing of the device so that said parts extend substantially in the same direction.

11. A device for use in playing pool or 125 billiards, comprising a base adapted to rest on a pool or billiard table and having sides converging horizontally substantially to an apex, an upright projecting from said base adjacent the apex portion thereof, and a cue 130

guide carried by said upright, said guide being arranged to guide the cue for movement in a substantially vertical direction above and into engagement with a pool or billiard ball.

12. A device for use in the playing of pool or billiards, comprising a base or support, and a cue guide for guiding the cue for movement in a substantially vertical direction above and into engagement with a pool

or billiard ball, said guide being connected to said base or support and adjustable relatively thereto upwardly and downwardly to a plurality of operative positions corresponding to different heights above the pool or billiard table.

In testimony whereof I have signed my name to this specification.

WILLIAM HENRY HARRISON.
